DESIGN FOR AN EDUCATIONAL RULE

Reinhold V. Erk, Waynesville, N. C.

Application July 21, 1934, Serial No. 52,665

Term of patent 14 years

To all whom it may concern:

Be it known that I, Reinhold V. Erk, a citizen of the United States, residing at Waynesville, in the county of Haywood and State of North Carolina, have invented a new, original, and ornamental Design for Educational Rules, of which the following is a specification, reference being had to the accompanying drawing, forming part thereof.

The figure is a perspective view of a rule showing my new design.

I claim:

The ornamental design for an educational rule, as shown.

REINHOLD V. ERK.
